UNITED STATES PATENT OFFICE.

ROBERT B. CHRITTON, OF ENID, OKLAHOMA TERRITORY.

FOLDING CRATE.

SPECIFICATION forming part of Letters Patent No. 699,078, dated April 29, 1902.

Application filed January 3, 1902. Serial No. 88,300. (No model.)

To all whom it may concern:

Be it known that I, ROBERT B. CHRITTON, a citizen of the United States, residing at Enid, in the county of Garfield and Territory of 5 Oklahoma, have invented a new and useful Folding Crate, of which the following is a specification.

This invention relates to folding crates particularly adapted for use in shipping poultry.

10 The object of the invention is to provide a simply-constructed and thoroughly-efficient form of folding crate which is adapted to be folded into compact form for return shipment and wherein the parts shall be so disposed as 15 mutually to brace and strengthen each other when the crate is set up for use.

With these and other objects in view, as will appear as the nature of the invention is better understood, the same consists in the 20 novel construction and combination of parts of a folding crate, as will be hereinafter fully described and claimed.

25 In the accompanying drawings, forming a part of this specification, and in which like numerals of reference indicate corresponding parts, there is illustrated a form of embodiment of the invention capable of carrying the same into practical operation, it being understood that the elements therein exhibited 30 may be varied or changed as to shape, proportion, and exact manner of assemblage without departing from the scope of the invention, and in the drawings—

Figure 1 is a view in perspective exhibiting the crate set up for use, one of the top slats or bars being shown partly withdrawn to permit insertion of the arm within the 35 crate for the removal of poultry. Fig. 2 is a view in perspective showing one side and end 40 in the position they occupy when the crate is set up and the other side and end in the position they occupy preparatory to folding up the crate. Fig. 3 is a view in transverse section showing the position occupied by the 45 parts when the crate is folded up for reshipment. Fig. 4 is a fragmentary detail view showing the connection between two of the members.

The crate of the present invention comprises a bottom 1, preferably composed of 50 slats, two ends 2, adapted to fold inward on the bottom, as shown in Figs. 2 and 3, and

two three-membered sides, whereof the members 3 and 4 constitute one side and the member 5 one section of the top. All of the parts 55 of the crate are by preference constructed of slats, although, if preferred, the sides, ends, and top may be made partly of wood and partly of woven or meshed wire, such as commonly employed in connection with crates of 60 this character, and as this will be obvious detailed illustration thereof is deemed unnecessary. The members 3 of the sides are rigidly associated with the bottom and are positively held from inward movement by cross-braces 65 6, as clearly shown in Figs. 1 and 2. The ends of the side members carry cleats 7, which not only subserve the function of shielding these parts from injury and giving added 70 rigidity to the structure, but also serve as a means for holding the slats constituting the parts assembled at the proper distance apart, the means of attachment between the cleats and the slats being through the agency of 75 nails or rivets 8. The top members 5 are associated with the side members 4 through the medium of ordinary strap-hinges 9, which are by preference let into the slats of the parts with which they coact, thereby to obviate the 80 presentation of an obstruction and to permit the parts being folded as close together as possible, the members 4 of the sides being hinged to the members 3 by providing the cleats carried by the members 4 with extensions 10, which work between the cleats of the members 85 3 and the ends of the top slats thereof and are held associated therewith by nails or screws 11, that hold the upper ends of the cross-braces 6 associated with the sides. The 90 opposed ends of the cleats of the members 3 and 4 on the side of the crate are outturned to present stops 12, which operate to limit outward movement of the members 4, as will be clearly understood by reference to Fig. 1. The ends 2 are held associated with the bottom by ordinary hinges 13, and the top slat or bar of each end is provided with a plurality of tenons 14, adapted to fit between the slats of the top sections, thereby to hold these 95 rigidly associated with the said ends. 100

One of the top sections is provided with a detachable slat 15, by which to permit of insertion of the arm into the crate for removing poultry, and suitable fastening means, as a

bolt 16, to interlock with an opening in the top slat of each end section, thereby to hold the top sections against being accidentally opened.

- 5 The under side of the end of each of the slats of the top sections is rabbeted at 17 to present stops 18 to engage with the under sides of the top slats of the ends, thereby securely locking the said ends against inward movement when the top sections are bolted down in position, so that all danger of collapse of the crate in being shipped or handled will in a positive manner be obviated.

10 To connect and brace the slats of the ends, cleats 19 are employed, which are held associated with the ends by rivets or nails 20.

15 It will be seen from the foregoing description that by reason of the manner in which the sides are constructed that the crate when folded up will occupy but small space and that when set up all of the parts thereof operate mutually to brace each other, so that a crate constructed in accordance with this invention will be of the highest efficiency and 20 durability in use and may be manufactured and sold at a low figure.

25 Having thus fully described my invention, what I claim as new, and desire to secure by Letters Patent, is—

- 30 1. A crate comprising a bottom, ends hinged thereto and adapted to fold inward thereon, and three-membered sides, the lower member

of each being rigidly associated with the bottom and diagonally braced against inward movement, the intermediate members being hinged to the bottom members and held against outward movement in a vertical line, and the upper members being adapted to fold over and interlock with the ends and to constitute the top sections.

35 2. In a crate, ends cut away to provide tenons at their upper edges, in combination with top sections adapted to fold over on the ends and to engage the tenons, the under sides of the ends of the top section being cut away 40 to provide rabbets to interlock with the top portion of the ends and bear against the inner surfaces thereof, substantially as and for the purpose specified.

45 3. In a crate, the combination with a bottom, of ends hinged thereto, three-membered sides carried by the bottom, and reinforcing cleats carried by the end portions of the sides, and having flanged projections to constitute stops to limit the outward movement of the 50 sides, substantially as described.

55 In testimony that I claim the foregoing as my own I have hereto affixed my signature in the presence of two witnesses.

ROBERT B. CHRITTON.
